UNITED STATES PATENT OFFICE

2,352,360

PLYWOOD LIFEBOAT

Ludwig S. Baier, Portland, Oreg.

Application November 8, 1943, Serial No. 509,464

6 Claims. (Cl. 9—23)

My invention, which relates to the art of boat building, has particular reference to life boats.

Primarily, the invention has for its object to provide a light-weight, strong and relatively inexpensive-to-build life boat to carry a maximum number of persons.

Again, it is an object to provide a life boat employing a minimum amount of metal in its hull construction.

Other objects will in part be obvious and in part be pointed out hereinafter.

To the attainment of the aforesaid objects and ends the invention still further resides in the novel details of construction, combination and arrangement of parts, all of which will be first fully described in the following detailed description, and then be particularly pointed out in the appended claims, reference being had to the accompanying drawing, in which—

Figs. 1^A and 1^B, when joined on the lines C—D comprise a longitudinal section of a life boat embodying my invention, taken at approximately the mid-ship.

Fig. 2 is a detail top plan view of a portion of the stern of the boat.

Fig. 3 is a detail vertical section of the stem of the boat.

Fig. 4 is a detail plan view of a modification hereinafter again referred to.

In the drawing, in which like numerals and letters of reference indicate like parts in all the figures, 1 is the stem iron which comprises a body having flanges 2 and which extends from the sheer to the keel. The stem iron has its flanges widened adjacent its upper end as at 3 for a purpose presently understood.

A pair of spaced metal plates 4 are welded, as at w, to the stem iron 1. A pin 46 passes through these plates 4 and through the shell and through the widened portions 3 of the stem iron, the pin being riveted over at its ends. Spacer pipes 45 are located on the pin between the plates 4 and the portions 3. The spacers 45 also serve as braces for the plates 4.

Pivoted on the pin 46 is the hook 53 that holds the boat-lowering tackle link 57 while lowering the boat from the deck of a ship, of which more will be said later.

The stern post 5, like the stem iron 1, is made of metal with flanges 6 and widened portions 7. Spaced plates 8 are also welded at w to the stern post 5, there being a pin 46 and spacers 45 employed as at the stem of the boat. Pivoted on the pin 46 of the stern-disengaging-apparatus is a

hook 53 for the aft link of the boat lowering tackle.

Both fore and aft, between the plates 4—4 and 8—8, is pivoted at 56 a weighted latch 55 which normally engages the pivoted hook 53, a stop in 54 serving to hold the hook 53 against turning in one direction behind a predetermined position (see Fig. 3). An eye bolt 47 passes through each pair of plates 4 and 8 and carries a spacer 52 between the plates.

A pulley 51 is mounted on each eye bolt, over which pulley the release cable 49 passes and has one of its ends connected to the weighted end of latch or lever 55.

The keel 10 of the boat is preferably made of oak and the keelson 11 is preferably made of fir.

The keel 10 and keelson 11, and the plywood shell 12 are secured together by bolts 19, a waterproof cement being applied to all faying surfaces.

Disengaging cables, indicated by dotted lines 49 in Figs. 1^A—1^B, pass through guides 48; at the aft end of the boat the fore and aft cables 49 are connected to a pull member 50. By pulling on member 50 the tiller man can release the fore and aft hooks 53 to free the boat from the launching tackle. It will be seen by reference to Figs. 1^A—1^B that the releasing gear is rigidly mounted directly on the stem and stern irons. Thus the weight of the boat as it hangs from the suspending tackle, including the load, is carried by the stem and stern irons, which stem and stern irons actually serve as two hooks that cradle the load, extending to the ends of the keel.

61 designates a steel liner and 62 a steel keel-guard at the bow end of the boat. At the stern end of the boat a stern plate 63 is welded to the stern post 5 and set into the keel 10 to which it is riveted and bolted at 19.

In Fig. 4 I have shown horizontally disposed gusset plates 45^x welded to the plates 3 and the plates 4 (or 8 as the case may be), in lieu of the pipes 45 and the extensions of the pins 46.

The general construction of the boat may be that disclosed in my application filed June 1, 1942, Serial No. 445,327, now Patent No. 2,341,010, of which the present application is continuation in part.

The construction of the stem and stern of the boat constitutes the claimed subject matter of the present application, while the seam construction constitutes the claimed subject matter of my original application aforesaid.

The stem and stern construction herein described enables the plywood shell to be directly fastened to the posts and the releasing tackle

being welded and braced to the stem and stern posts strengthens these posts so that thin sheet metal may be used in the construction of the posts.

From the foregoing description, taken in connection with the accompanying drawings, it is thought the construction and advantages of the invention will be clear to those skilled in the art.

What I claim is:

1. In a life boat having a keel and keelson, solid wood frames and a plywood shell; metal stem and stern posts secured to the fore and aft ends respectively of the shell and extending down to the keel, said stem and stern posts having side flanges of increased width at their upper ends, pairs of parallel plates integrally secured to the stem and stern posts and spaced apart at the mid-plane of the boat, spacers between said plates and said upper ends, and pins passing through said spacers, said plates, the shell and said upper ends and having their outer ends riveted over, thereby strengthening the prow and stern of the boat.

2. In a life boat having a keel and keelson, solid wood frames and a plywood shell; metal stem and stern posts secured to the fore and aft ends respectively of the shell and extending down to the keel, said stem and stern posts having side flanges of increased width at their upper ends, pairs of parallel plates integrally secured to the stem and stern posts and spaced apart at the mid-plane of the boat, spacers between said plates and said upper ends, pins passing through said spacers, said plates, the shell and said upper ends and having their outer ends riveted over, thereby strengthening the prow and stern of the boat, lowering tackle engaging hooks pivoted between the plates of each pair, a hook latch also pivoted

between the plates of each pair to hold the hook, and hook-releasing tackle connected with the fore and aft latches and operable by one person for releasing the fore and aft latches simultaneously.

3. The life boat of claim 1 wherein a stern plate is welded to the stern post.

4. In a life boat having a keel and keelson, solid wood frames and a plywood shell; metal stem and stern posts secured to the fore and aft ends respectively of the shell and extending down to the keel, said stem and stern posts having side flanges of increased width at their upper ends, pairs of parallel plates integrally secured to the stem and stern posts and spaced apart at the mid-plane of the boat, spacers between said plates and said upper ends, thereby strengthening the prow and stern of the boat.

5. In a life boat having a keel and keelson, solid wood frames and a plywood shell; metal stem and stern posts secured to the fore and aft ends respectively of the shell and extending down to the keel, said stem and stern posts having side flanges of increased width at their upper ends, pairs of parallel plates integrally secured to the stem and stern posts and spaced apart at the mid-plane of the boat, and gusset plates connecting said parallel plates with said side flanges, thereby strengthening the prow and stern of the boat.

6. In a life boat having a wooden keel and keelson, solid wood frames and a plywood shell; metal stem and stern posts secured to the fore and aft ends respectively of the shell and extending down to the keel, the stem post iron extending over the bow end of the keel; and a metal keel guard at the bow end of the boat underlying the keel and the portion of the stem post iron in advance of the keel.

LUDWIG S. BAIER.
